(57) **CLAIM**

The ornamental design for an exercise apparatus for resistance training, as shown and described.

DESCRIPTION

FIG. 1 is a frontal perspective view of an exercise apparatus for resistance training having a textured surface for use by a person shown in broken lines, a right handle assembly, and a left handle assembly, wherein said right and left handle assemblies being in a storage position.

FIG. 2 is a front elevation view thereof.

FIG. 3 is a rear elevation view thereof.

FIG. 4 is a right-side elevation view thereof.

FIG. 5 is a left-side elevation view thereof.

FIG. 6 is a top plan view thereof.

FIG. 7 is a bottom plan view thereof.

FIG. 8 is a side perspective view thereof, shown in condition of use with the right handle extended by an unclaimed person.

FIG. 9 is a side perspective view thereof, shown in condition of use with the left handle extended by an unclaimed person; and,

FIG. 10 is a side perspective view, shown in condition of use with both the right and left handles extended by an unclaimed person.

The broken lines showing a textured surface in FIGS. 1 and 6 represent unclaimed surface ornamentation and the broken lines showing a woman in FIGS. 8–10 illustrate environmental structure, which form no part of the claimed design.
